UNITED STATES PATENT OFFICE.

CHARLIE TOOTELL, OF MELBOURNE, VICTORIA, AUSTRALIA.

CONTRIVANCE TO PROVIDE FOR THE FREE EXIT OF FLIES FROM BUILDINGS AND TO PREVENT THEIR REENTRANCE.

1,046,902.

Specification of Letters Patent. Patented Dec. 10, 1912.

Application filed January 27, 1911. Serial No. 604,963.

To all whom it may concern:

Be it known that I, CHARLIE TOOTELL, of the Engineers' Depot, Alexandra avenue, Melbourne, Victoria, Australia, have invented an Improved Contrivance to Provide for the Free Exit of Flies from Buildings and to Prevent Their Reentrance, of which the following is a specification.

This invention has been devised in order 10 to provide some simple and inexpensive yet thoroughly efficient means for removing flies from the interior of dwelling houses and other buildings and at the same time preventing them from regaining an entrance to 15 said buildings. It is generally well known to adopt for this purpose a wire gauze cone so arranged that the larger diameter opens inwardly while the apex or small opening projects outwardly, the cone being mounted 20 in a wire blind or door. In accordance with the present invention, cones of this kind are mounted on sheets of metal, wood or similar opaque material which is of particular advantage as the flies landing on the opaque 25 metal or wood appear to be attracted by the light passing through the cones and are thus induced to pass into the outer atmosphere.

The invention further resides in other 30 features of construction as hereinafter described.

In order that the invention may be readily understood it will be described with reference to the accompanying drawings, in which—

35 Figure 1 is a side elevation of a cone the application of which, as hereinafter described, constitutes the essential feature of this invention. Fig. 2 is a vertical central section of said cone, and Fig. 3 illustrates 40 the application thereof to a piece of wire gauze such as is used for fly doors, blinds or the like. Fig. 4 is an elevation of the construction illustrated in Fig. 3. Figs. 5 and 45 6 are similar views to Figs. 3 and 4 illustrating the application of the invention to a wooden board, piece of sheet metal or other material adapted to be secured in position in a window frame, doorway, ventilator frame, skylight or other desired part 50 of a dwelling or other building. Figs. 7 and 8 are respectively a section and plan illustrating the invention constructed in a sheet of glass, metal or other material admitting of the conical or funnel shaped projections being cast, stamped or otherwise 55

formed integral with said sheet. Figs. 9 and 10 are perspective views illustrating, by way of example, modified conical or funnel shaped projections.

The same numerals of reference indicate 60 the same or corresponding parts throughout the figures.

The essential feature of this invention consists in the use of conical or funnel shaped projections 1 as illustrated in the 65 drawings, permanently or temporarily fixed in the window, door, fan-light, fly door, fly blind, ventilator or other desired part of a dwelling or other building construction, in such a way that the smaller diameter of 70 said conical or funnel shaped projection projects outwardly, said end being provided with a small hole 2 which allows the flies to escape from the interior of the building or other structure to which it is applied, while 75 the larger diameter 3 or base of the conical or funnel shaped projection is set in, or is flush with, the surface of the gauze 4, piece of wood, sheet of glass, metal or other material to which it is attached, or upon or 80 from which it is formed. Cones may be constructed as indicated in Figs. 1 to 6 of wire gauze and may be provided with a rim or flange 5 around their larger end to facilitate their insertion or attachment to 85 a sheet of gauze for instance as illustrated in Figs. 3 and 4. It will, however, be readily understood that other means for securing or attaching the cones in position may be employed.

90 Sheets of gauze provided with funnels or cones as above described may be cut to suit different sized windows and may be fitted in position in any way found most convenient and the sheet of gauze may be fitted with an outer frame as indicated at 6 in Figs. 3 and 4. If preferred, the frame, sheet or board carrying the cones may be made adjustable in length (as indicated by way of example in Figs. 5 and 6) sliding extension pieces as 7 being mounted so that they can be adjusted or slid in or out to increase or decrease the length of the board or sheet according to the width of the opening in which it is to be secured.

100 If preferred, the sheets of gauze or other material upon which the cones are formed or attached can be perforated or otherwise made so that strips can readily be cut off to reduce it to the exact length required to 110

suit the window or other opening or place where it is to be fitted.

The cones may be formed integral with sheets of glass as indicated in Figs. 7 and 8 said cones 1 being molded out of the same material as the plate or sheet 4; or, instead of glass any other suitable material such as celluloid or metal might be used, the essential feature, so far as this invention is concerned, being that such sheet has one or any number of larger or smaller cones projecting from it with the larger diameter or mouth of the cone directing into the building while its apex with small outlet 2 therein projects away from or outside the building. Although the cones are conveniently made circular in form, they can be pyramidal as indicated in Fig. 9 or can be in the form of a V-shaped ridge or corrugation as indicated in Fig. 10 and be provided with small holes 2 in the apex of the conical ridge or can be made octagonal or of any other polygonal shape, the only essential being, as above indicated, that they shall lead from the larger opening at the inner end to a small opening at the outer end.

In operation, if the invention above described is placed, in say, the upper part of a window, the flies will, as it were, be automatically extracted from the building. They move about over the window opening or gauze forming the screen, become attracted into the funnel shaped opening leading to the outside atmosphere and having passed through the cones are, in practice, pre-

vented from again returning. In this way, a dwelling or other building will be rapidly cleared of flies in a thoroughly efficient manner and without the objectionable features incidental to the use of the ordinary means 40 of coping with the pests.

The contrivance is easily fitted in position and can be applied to ordinary ventilators, the gauze conical or funnel shaped projections serving to remove the flies from the 45 interior of the building without in any way interfering with the ventilation.

The invention can be made comparatively attractive in appearance, the conical or funnel shaped projections made of glass 50 or other similar material not being a disfigurement and they can, if desired, be inserted in lead lights by securing them in position in the ordinary manner by means of lead channel bars. 55

I claim:

An adjustable frame comprising a board of opaque material with holes cut therein in combination with suitably transparent cones having a small hole at or near the 60 apex, said cones being adapted to be fitted in said holes and project therefrom substantially as and for the purposes specified.

In witness whereof I have hereunto set my hand in the presence of two witnesses. 65

CHARLIE TOOTELL.
